DESIGN FOR AN ACETYLENE TORCH

Donald H. Black, Salem, Oreg.

Application July 13, 1942, Serial No. 107,515

Term of patent 14 years

To all whom it may concern:

Be it known that I, Donald H. Black, a citizen of the United States, residing at Salem, county of Marion, State of Oregon, have invented a new, original, and ornamental Design for Acetylene Torches, of which the following is a specification, reference being had to the accompanying drawing, forming part thereof.

Fig. 1 is a side elevational view of an acetylene torch showing my new design; and
Fig. 2 is a top plan view thereof.

I claim:

The ornamental design for an acetylene torch, as shown.

DONALD H. BLACK.
